UNITED STATES PATENT OFFICE

158,048

SANDWICH

Frank H. Cepl and Ethel M. Cullen,
Los Angeles, Calif.

Application July 5, 1949, Serial No. 3,696

Term of patent 14 years

(Cl. D8—1)

To all whom it may concern:

Be it known that we, Frank H. Cepl and Ethel M. Cullen, citizens of the United States, residing in the city of Los Angeles, county of Los Angeles, and State of California, have invented a new, original, and ornamental Design for Sandwich, of which the following is a specification, reference being had to the accompanying drawing, forming a part thereof, and in which drawing:

Fig. 1 is a side elevation of a sandwich, embodying our new design,

Fig. 2 is a perspective view,

Fig. 3 is a transverse sectional view taken on the line 3—3 of Fig. 1, and

Fig. 4 is an enlarged transverse section taken on the line 4—4 of Fig. 1 to more clearly show the exterior contour at that point.

We claim:

The ornamental design for a sandwich, substantially as shown.

FRANK H. CEPL.
ETHEL M. CULLEN.
